United States Patent Office.

JOHN BEACH, OF DE RUYTER, NEW YORK.

Letters Patent No. 85,508, dated January 5, 1869.

IMPROVEMENT IN WIND-WHEELS.

The Schedule referred to in these Letters Patent and making part of the same.

To all whom it may concern:

Be it known that I, JOHN BEACH, of De Ruyter, in the county of Madison, and State of New York, have invented a new and useful Improvement in Windmills; and I do hereby declare that the following is a full, clear, and exact description thereof, which will enable those skilled in the art to make and use the same, reference being had to the accompanying drawings, forming part of this specification, in which—

Figure 1 is a side elevation, with the supporting-column shown in section, and

Figure 2 shows a front view of the sail.

Similar letters of reference indicate corresponding parts.

In the accompanying drawings—

A is the supporting-column;

B is the main shaft;

C is the balance-wheel; and

D is the sail.

The sail is made up of several sections, d^1 , d^2 , d^3 , &c., which are so arranged, with relation to each other, as to form a continuous spiral sail around the shaft B.

The forward edge of each section of the sail is attached to an arm, S, which is secured to the main shaft B in a fixed manner, while the rear edge, or corner, e, fig. 2, of the section is left free to swing in a direction parallel to the main shaft B; but this swinging motion is resisted by a spiral spring, f, one end of which is secured to the sail, and the other end to the cross-bar or brace, g, which connects the outer ends of two of the arms s.

The sections of the sail are made of cloth, or other flexible material, stretched over a frame, which will keep the rear edge of a section extended, but they can be made of wood or sheet-iron, and their forward edges hinged to the arms s.

The arms s have also a second set of braces, h h, by which they are secured to each other, in addition to the outer braces g g, which hold the rear edges of the sails to the wind by means of the springs f f.

The object of the balance-wheel C is to balance the shaft B on the supporting-column A.

The supporting-column consists in a revolving sleeve, a, having a seat on the exterior upper part of A, and provided with two bearings, b b, for the shaft B, there being sufficient space between the bearings b b for them to straddle the gears m.

The column A has a hole down through its centre, for holding the vertical shaft K, and it is supported on legs, n n, to make room for a gear, k, or band-wheel, which delivers the power of the apparatus.

The sail D is always blown around to leeward of the supporting-column, and serves both as a vane and sail.

When the wind is too strong, the springs f yield, and allow the sections or sails to swing more in line with the main shaft B, and thereby present a smaller front to the wind.

By these means I obtain a mill which is cheap, simple, and efficient.

Having thus described my invention,

What I claim as new, and desire to secure by Letters Patent, is—

The swinging sections or sails d, shaft and arms B s, braces g h, and springs f, all constructed and operating as herein shown and for the purpose described.

The above specification of my invention signed by me, this 23d day of June, 1868.

JOHN BEACH.
